US00D370017S

United States Patent [19]

Tsai

[11] **Patent Number:** **Des. 370,017**[45] **Date of Patent:** ****May 21, 1996**

[54] **AUXILIARY UNIT FOR AUGMENTING COMBUSTION RATE OF AUTOMOBILE**

[76] Inventor: **Chung-Tie Tsai, P.O. Box 96-405, Taipei 10098, Taiwan**

[**] Term: **14 Years**

[21] Appl. No.: **34,334**

[22] Filed: **Feb. 1, 1995**

[52] U.S. Cl. **D15/5**

[58] Field of Search **D15/1-5; 123/572-574**

Primary Examiner—Ralf Seifert

[57] **CLAIM**

The ornamental design for an auxiliary unit for augmenting combustion rate of automobile, as shown.

DESCRIPTION

FIG. 1 is a perspective view;
FIG. 2 is a front elevational view;
FIG. 3 is a right side elevational view;
FIG. 4 is a rear elevational view;
FIG. 5 is a left side elevational view;
FIG. 6 is a top plan view; and,
FIG. 7 is a bottom plan view.

1 Claim, 2 Drawing Sheets

FIG. 1

FIG. 2

FIG. 3

FIG. 4

FIG. 5

FIG. 6

FIG. 7
